UNITED STATES PATENT OFFICE.

OTTO JAEGGE, OF GLENDALE, NEW YORK, ASSIGNOR TO PEERLESS SILK MILLS, INC.,
OF NEW YORK, N. Y., A CORPORATION OF NEW YORK.

BINDING FOR SHOE-TOPS.

1,217,002.

Specification of Letters Patent. Patented Feb. 20, 1917.

Application filed December 9, 1915. Serial No. 65,932.

To all whom it may concern:

Be it known that I, OTTO JAEGGE, citizen of the United States of America, residing at Glendale, Queens county, New York, have 5 invented a new and useful Improvement in Binding for Shoe-Tops; and I do hereby declare the following to be a full, clear, and exact description of the same.

This invention relates to bindings for shoe 10 tops, laces and the like and process for applying same and has for its object to reduce the cost and increase the efficiency and sightliness of shoe binding and more particularly to provide in a single strip 15 a binding that will have a maximum of tensile strength and at the same time present a neat appearance when the shoe is worn.

While herein I describe minute details of the construction, operation and uses of 20 the invention, it is understood that I am not limited to these, as these details may be greatly varied without departing from the scope of the invention as claimed.

In the accompanying drawing showing 25 one of many possible embodiments of the invention,

Figure 1 is a side elevation of a portion of a shoe top provided with one form of binding;

Fig. 2 is a face view of the binding strip; Fig. 3 shows a section on an enlarged scale on line 3 . . . 3 of Fig. 1, and

Fig. 4 is a sectional view showing a step in the manufacture;

Fig. 5 is a fragmental side elevation showing another form of the binding;

Fig. 6 shows a section on line 6 . . . 6 of Fig. 5.

Referring to Figs. 1 to 3 the binding 10 shown at the top of a shoe upper 11, shows my invention applied to the so called French binding.

The binding consists of an ornamental part 12 comprising silk or other ornamental 15 warp threads, and a part 14 comprising cotton or other strong warp threads. The cross threads are cotton and cross both sets of the warp threads. The threads may be

of any color or shade, but it is sometimes better to have the sets of warp threads of 50 contrasting color or shade in order that the operators may easily distinguish them when applying the binding.

The binding strip is first stitched as at 15 (Fig. 4) with its outer face against the 55 outside face of the shoe top, the silk side of the binding strip being next to the edge. The binding is then carried over the edge of the shoe top and cemented to the inner face of the shoe top as shown in Fig. 3, after 60 which the lining 16 of the shoe top is stitched in place with the line of stitches 17. The object of the cementing is merely to hold the binding in place until the whole is 65 stitched together by the stitches 17.

Figs. 5 and 6 show my invention embodied in a "machine binding."

In this case as in the first described form, the binding 20 applied to the shoe upper 21 comprises an ornamental part 22 and a 70 strong part 24.

The shoe upper 21 and the lining 26 are cemented together at the upper part back-to-back (Fig. 6) and the binding 20 is applied and stitched in place with stitches 27 75 with the usual binding machine, the ornamental part lying to the outside as shown.

This method of applying the binding is economical both in material and number of operations required to apply and is 80 slightly, efficient and lasting.

I claim as my invention:

A binding for shoe tops having fine silk warp threads on one edge portion and coarse cotton warp threads on the opposite edge 85 portion lying contiguous to the silk warp threads, and cotton weft threads common to both warp threads.

In testimony whereof, I have signed my name to this specification in the presence of 90 two subscribing witnesses.

OTTO JAEGGE.

Witnesses:

CORNELIUS HOVING,
H. M. KILPATRICK.
